UNITED STATES PATENT OFFICE.

RALPH JACKSON, OF COVENTRY, ENGLAND, ASSIGNOR TO ALFRED HERBERT LIMITED, OF BUTTS, COVENTRY, ENGLAND, A BRITISH COMPANY.

COAL-PULVERIZING MACHINE.

Application filed April 13, 1926, Serial No. 101,817, and in Great Britain May 5, 1925.

This invention relates to a pulverizing machine of the type shown in the U. S. patent to Blyth Reissue No. 16,229, dated Dec. 15, 1925, and more particularly to a machine 5 constructed as shown in my co-pending application Serial No. 101,236, filed April 12, 1926.

For many purposes coal pulverizing machines with large output but small overall 10 dimensions are required, but with certain constructions it is inadvisable to increase the size beyond a certain limit, as the efficiency falls off.

According to this invention, a coal pul- 15 verizer comprises a pair of machines combined together to form a unit, the machines being each of efficient size and arranged back to back and provided with a common driving shaft.

20 The two machines may be detachably mounted upon a common base adapted, if desired, to carry a driving motor and also reduction drive mechanism if necessary. Also two such units may be combined to 25 form a single machine.

Referring to the drawings illustrating one embodiment of my invention and in which like reference numerals indicate like parts, Fig. 1 is a plan view of a unit constituted by 30 two machines arranged back to back, and a second and similar unit combined with the first unit so that they are symmetrical about the line X, Y, and

Fig. 2 is an enlarged plan view of one of 35 the machines, with parts broken away to show the internal construction.

In the preferred construction illustrated there is a base plate 2 to each end 3 of which is bolted a pulverizing machine 4, these being arranged back to back, or, in other words, with their driving ends facing one another. This leaves the fan casings 5 easily accessible, which is particularly important where the fan casing, or its cover, is hinged 45 to the body of the machine.

There is employed a common driving shaft 6 which enters both machines and carries the usual rotating elements, and this shaft is driven from a single power source, 50 preferably carried by the base plate. For example, the base plate may have an extension 7 adapted to support an electric motor 10 driving the shaft through right angle gearing 8, generally of a reducing type.

55 It is preferred that there be a single feed-

ing device for both machines, this being of any suitable nature delivering through a central aperture 9, though in some cases there may be separate feeding devices with independent control and adjustment. Coarse 60 material fed to the opening 9 slides down a chute 11 leading to each pulverizing chamber. Usually also the driving shaft 6 would be solid from end to end, though it may be in sections with intermediate clutches 65 between the central portion carrying the gearing and each machine, so that either machine can be stopped.

Each machine may be constructed as desired, but as illustrated in Fig. 2, it may 70 comprise a rotor disk 13 mounted on the shaft 6 within the pulverizing chamber 4 which carries on each side concentric rows of revoluble pegs or beaters 14 arranged to co-operate with concentric rows of stationary pegs 15 suitably attached to the casing walls. A diaphragm plate 16 separates the pulverizing chamber from the fan chamber 5. This diaphragm plate has a large central aperture 18 through which the pulverized material is drawn by the air current produced by the fan 19 and subsequently discharged through the outlet 20, (Fig. 1).

The diaphragm plate and the fan casing are each hinged to the pulverizing chamber 85 4 at the point 21. The bearing 22 for the end of the shaft carrying the fan is adapted to be withdrawn endwise from the fan casing, after removal of the cap 23 and the shaft collar 24. The bearing 22 is in the flanged 90 bush or sleeve 25 and is removed by withdrawal of the bush from the bracket 26, which latter at its lower part (not shown) is attached to the casing. After the bearing and the flanged sleeve 25 are removed, the 95 sleeve 28 fixed on the shaft 6 and provided with a disk 29 extending into the fan casing and at the same time filling the aperture 30 in the latter's end wall, can also be removed. This leaves an annular space about the end 100 of the shaft which allows the casing to swing about its hinge 21 without fouling the end of the shaft. When the casing has been swung open the fan wheel 19 is exposed, and the latter is so secured to its shaft that it can be quickly detached therefrom.

The diaphragm plate 16 is also hinged to the pulverizing chamber and the large central aperture 18 permits it to be swung about its hinge without interfering with the end 110

of the fan shaft. This construction permits a ready access to the interior of the pulverizing chamber.

It will be apparent that coarse material 5 delivered by a single feeding mechanism to the aperture 9 will divide, and part will pass down each chute 11 into the pulverizing chamber. The material is then struck by 10 the rapidly revolving pegs 14 on the inlet side of the rotor disk, and thrown outwardly while being reduced by impact and attrition 15 between the stationary and revolving pegs. The partially pulverized material passes around the periphery of the disk and is drawn inwardly towards the centrally located outlet 18 by the air current produced by the fan 19. The material is pulverized to a fine powder by the action of the revolving 20 and stationary pegs on the outlet side of the disk, and only the smallest particles can escape through the outlet, since the tendency of centrifugal force is to throw the material away from the axis of the machine. The fine material which enters the fan chamber 25 is delivered on the air current through the outlet 20 and is transported to any desired point. The two machines forming the unit are driven by the single motor 10, which is so arranged that it will not interfere with 30 the opening of the machines for inspection or repair.

In some instances two units may be combined to form a single machine having a very considerable output. Thus there might 35 be two base plates 2 arranged parallel to one another, each carrying at each end a machine of the kind referred to. The two common driving shafts would then be connected to a single driving means arranged 40 between the two base plates, and, if desired, the two base plates may be combined into one supporting portion for the single driving means. Thus the base plate may be rectangular or roughly H-shaped. In the 45 latter case, the connecting portion of the H would form the base for the driving means, which might be an electric motor or steam turbine.

Such an arrangement is clearly indicated 50 in the drawing, the second unit being shown

to the right of the line X, Y, and having corresponding reference numerals. The electro-motor 10 occupies the part of the bed between the two units.

By this means a machine of large output, 55 small overall dimensions, and low cost is provided, whilst high efficiency is maintained.

What I claim as my invention and desire to secure by Letters Patent of the United 60 States is:—

1. A pulverizing apparatus comprising a one piece casing having two spaced centrally located pulverizing chambers, means forming a fan chamber outside of each pulverizing chamber, a single shaft passing through the chambers centrally thereof, and driving connections to the central portion of said shaft between the pulverizing chambers. 65

2. A pulverizing apparatus comprising a one piece casing having two separate pulverizing devices mounted therein in spaced relation, a fan casing outside of each pulverizing device, a single shaft passing through the casing centrally thereof and adapted to drive the pulverizing devices and fans simultaneously, means for driving said shaft, means forming a single inlet for coarse material to the central portion of the casing, and means forming an outlet for pulverized material connected to each fan casing. 70

3. A pulverizing apparatus comprising two spaced pulverizing chambers provided with outlet openings at their outer ends and 75 inlet openings at their inner ends, a common driving shaft passing through the two casings, revoluble pulverizing devices mounted on said shaft in said casings, means forming a fan chamber outside of and connecting 80 with the outlet openings, a fan in the chamber mounted on said shaft and arranged to draw a current of air and pulverized material through each pulverizing casing, means forming an inlet for coarse material to said 85 inlet openings, and means connected to said shaft to rotate the same. 90

In testimony whereof I have signed my name to this specification.

RALPH JACKSON.
